(57) **CLAIM**

The ornamental design for a carport with integrated photovoltaic panel, as shown and described.

DESCRIPTION

FIG. 1 is a top perspective view of a carport with integrated photovoltaic panel showing my new design;

FIG. 2 is a bottom perspective view thereof;

FIG. 3 is a front view thereof;

FIG. 4 is a rear side view thereof;

FIG. 5 is a right side view thereof, a left side view being a mirror image of the right side view;

FIG. 6 is a top view thereof; and,

FIG. 7 is a bottom view thereof.

Portions of the carport with integrated photovoltaic panel shown in broken lines form no part of the claimed design.
